TORPEDO EXPLODER

John M. Stockard, Washington, D. C.

Application November 17, 1949, Serial No. 127,902

18 Claims. (Cl. 102—17)

(Granted under Title 35, U. S. Code (1952),
sec. 266)

1

This invention relates to improvements in torpedoes, but more specifically in exploders for detonating the warhead when the torpedo strikes its target. As is common knowledge in persons acquainted with mechanisms of this sort, an exploder is a device fixed in the shell of the warhead and is surrounded by the main explosive charge. It is the function of the exploder to detonate said charge by contact of the torpedo with the target.

To properly serve its purpose the exploder must meet a number of established requirements among which are (a) to keep the exploder mechanism dormant while the torpedo remains housed in the torpedo tube and to keep it inoperative during the first part of its run so as to save the firing vessel from damage in case of a premature detonating action of said mechanism, (b) to insure the explosion of the torpedo when it strikes its target, and (c) to lock the exploder when the torpedo sinks in case of having missed the target, so that the main explosive charge cannot be detonated either by hitting bottom or by the sudden shock due to the collapse of certain portions of the torpedo shell under hydrostatic pressure.

Under this broad outline the invention has several principal objects, one of which, directed toward keeping the exploder mechanism initially dormant, is to provide an impeller shield for preventing a premature flow of water through the impeller channel, and to hold said shield down before the torpedo is inserted into the tube by means of a safety block which must be removed before the torpedo can enter the tube.

Another object of the invention, directed to the same purpose, is to prevent rotation of the impeller even when the torpedo is loaded into the tube, use being made to that end of a hinged shield which is held closed by the tube so that water driven through the tube may not enter the impeller channel with force enough to move the impeller.

Another object of the invention is to utilize the foregoing shield for two diverse purposes, first to prevent the flowing of a water stream through the impeller channel during the inactive status of the torpedo, second to deflect water from the slipstream after the torpedo is launched to direct the maximum current against the impeller.

Another object of the invention is to provide an indicator spindle as an auxiliary to the arming mechanism which, initially retracted, is progressively protruded from the exploder case beyond the surface of the warhead shell in the event of unpremeditated movement of the arming plunger from its safe position, which protrusion, if of suf-

ficient magnitude to show a dangerous degree of arming, will prevent the loading of the torpedo into the torpedo tube.

Another object of the invention is to utilize the arming plunger, in addition to its function of moving the explosive train into proximity with the firing pin and booster charge, for initially locking the firing pendulum and ultimately cocking the firing pin, these extremes representing the unarmed and armed conditions of the torpedo.

Another object of the invention is to insure the firing of the torpedo when it strikes the target, by providing a universally swingable pendulum which is deflectable in any angular direction opposite to the direction of deceleration of the torpedo, to displace the firing pin sear from the cocked firing pin.

Another object of the invention is to render the torpedo indefinitely inactive, hence safe, by providing a hydrostatically operable plunger locking the firing pin against movement from its cocked position in the event of sinking of the torpedo to the bottom, the increasing hydrostatic pressure acting through the plunger to swing a latch into an obstructing position in respect to the firing pin sear. Such action is strategically desirable so that a torpedo which misses will not warn the enemy of a torpedo attack by exploding when it sinks at the end of its run.

Other objects and many of the attendant advantages of this invention will be readily appreciated as the same becomes better understood by reference to the following detailed description when considered in connection with the accompanying drawings wherein:

Fig. 1 is a central, vertical section of the improved exploder, the mechanism being shown in its initial or unarmed position;

Fig. 2 is a central, vertical section of a portion of the exploder, showing the firing mechanism in the ready-to-fire or armed position;

Fig. 3 is a horizontal section taken substantially on the line 3—3 of Fig. 1;

Fig. 4 is a detail central, vertical section taken substantially on the line 4—4 of Fig. 3, some of the working parts being shown in skeleton form as though the section were taken centrally through Fig. 1, some of the mechanism being omitted, however, to avoid a needless repetition of parts;

Fig. 5 is a detail side elevation of the lower part of the exploder housing; and

Fig. 6 is a detail cross section taken on line 6—6 of Fig. 1.

In carrying out the invention, the warhead shell

10 is provided with an opening 11 large enough to expose the arming train housing 12 and to permit its being lifted out when the occasion demands. This housing fits inside of the largest-diamented and stepped part 13 of the exploder case 14 which extends inwardly of the torpedo. The flange 15 of the part 13 closely contacts the inside of the shell 10, and a seam 16 of welding at once permanently secures the case and seals the opening 11.

The exploder case 14 is surrounded by the main explosive charge of the warhead (Fig. 4). Its showing in Figs. 1 and 4 as though depending from the shell 10 was largely a matter of choice in illustration. Actually and in practice the exploder case may stand upright from the bottom of the warhead, in which position its weight will tend to assist in stabilizing the torpedo against rolling. The axis of the exploder is intended to be perpendicular to the axis of the torpedo and in a vertical plane.

Exploder housing 18 contains the working parts of the exploder per se and the booster charge 19 which is necessary in order that the relatively weak explosion of the small but sensitive percussion cap 20 shall cause the explosion of the main explosive charge in the warhead of the torpedo. This housing is mounted in the exploder case 14 against a watertight gasket 21. The terminal flange 22 of the housing 18 rests on a step in the part 13, to which it is secured by a number of bolts 24 (Fig. 1).

Bolts 25 (Fig. 4) secure the arming train housing 12 to the exploder housing 18 independently of the exploder case 14. This intercoupling is a practical convenience. By removing the bolts 25 the arming train housing 12 can be removed, as may be desirable for any one of a number of reasons, without disturbing the exploder housing 18 or its contents. Similarly, by removing the bolts 24 both housings 12 and 14 can be lifted out as a unit, so that the engagement between the worm 26 and wormgear 27 is not broken.

The worm 26 is part of a gear train carried by the housing 12 and projecting in part into the cavity 28 in the upper part of the housing 18. The remainder of the gear train consists of spur gears 30, 31 and 32 (Fig. 3) ending at the impeller 33 to the shaft 35 of which the gear 32 is affixed, all mounted in the arming train housing 12, and of wormgear 27 which is mounted on the exploder housing 18. The housing 12 is depressed in its outer face to define a channel 36 in which the impeller is rotated by a sufficiently strong flow of water. This rotation drives the wormgear 27 at the other end of the gear train, in turn rotating the arming screw 37 to the upper shaft end 38 of which the wormgear 27 is secured.

Initially, that is to say prior to loading the torpedo into the torpedo tube, a safety block 40 bears down on a shield 41, holding the latter in its closed position over most of the depression in the housing 12. This prevents the possibility of a premature flow of water through the channel 36, and the consequent possibility of driving the impeller to such an extent as to approach the armed condition of the exploder. The block 40 is secured to the housing 12 by a single brass screw 42. Said block protrudes beyond the largest diameter of a torpedo tube, hence must be removed before the torpedo can enter.

The presence of the safety block is a signal that the torpedo is unarmed and will remain unarmed until the block is removed. This can be

done either by backing the screw 42 out or, if it is not desired to interrupt the loading of the torpedo into the tube, the torpedo can simply be thrust into the tube whereupon the screw will shear. The safety block will then be knocked clear without injury to any part other than the screw, the block having first served its function of assuring that the impeller shield was held down until it entered the torpedo tube.

10. The shield is still held down, now by the wall of the torpedo tube. Even though water should be driven into the tube, as is possible in a high sea, water cannot enter the channel 36 with force enough to turn the impeller 33. It is not until the 15 torpedo is launched that the shield 41 swings open to the chain-line position in Fig. 1, whereupon it acts as a scoop to direct a stream of water against the impeller with maximum force. The shield thus serves two purposes. First, it excludes water to the extent of building up a stream in the channel 36, second, it becomes a scoop to deflect water from the slipstream into the channel to drive the impeller with full force.

To these ends the shield 41 is hinged upon bushings 43 (Fig. 3) in which the cylindrical ends of the shaft 35 have bearing. The shield has side plates 44 that ride the bushings, and thereafter converge into a single arm 45 to which one end of a spring 46 is connected. The other end of the spring is anchored to a lug 47 which, together with a lip 48, is secured to the housing 12 by a common screw. The lip confronts the water against the impeller and directs the water against the blades to the best advantage. When the shield is released, the 30 spring pulls a part of one of the side plates against a stop pin 49, thus limiting the open position of the shield.

Assuming the torpedo to have been launched from the torpedo tube, the spinning of the impeller 33 drives the gear train and rotates the arming shaft 38. This shaft is packed at 51 to exclude water from the inside of the exploder case 14, and is swiveled at 52 so that the rotation of the screw 37 will be translated only into a rectilinear movement of the arming plunger 53. The 40 screw 37 goes through an internally threaded insert 54 in the outer end of a bore 55 in the arming plunger. Initially the arming plunger assumes the "in" position shown in Fig. 1. In this position it performs two important but secondary functions.

At one side the arming plunger 53 has secured to it a key 56 which rigidly carries a ring 58. This ring initially embraces the firing pendulum 59 (Fig. 1). The pendulum consists of a weight that has an integral stem 60 which ends in a ball. The ball is socketed by a fitting 61 in a concavity in what can be called the head 62 of the exploder housing 18. This fitting is clamped against the head by a turreted ring 63 which also provides a base for the frusto-conically contoured spring 65. The small end of the spring engages the back of the pendulum, pushing outwardly against the pendulum to tend to keep it erect with respect to the head 62. Later on, when the torpedo strikes the target, the pendulum is deflected because of its inertia, thus firing the torpedo as is brought out below.

The ball and socket mounting of the pendulum 59 makes it universally swingable so that the deflection can take place in any angular direction. Under that premise the pendulum could be deflected even by a laterally directed blow while the torpedo is in an inactive status. However, the ring 58 embraces the pendulum and

at this time prevents any swinging so that the torpedo cannot be exploded by that means. The arming plunger 53 thus serves one of two secondary functions, namely to lock the pendulum in the unarmed status of the torpedo.

An angled passageway in that end of the plunger 53 opposite to the insert 54 contains the percussion cap 20 in one of its components and a number of explosive pellets 66 in its other component. The cap 20 is directed toward the firing pin 67, and ultimately registers with it, and the pellets 66 are directed toward the booster charge 19. But while the arming plunger 53 occupies the "in" position, the cap 20 is out of registration with the firing pin (Fig. 1), and the pellets 66 are spaced an appreciable distance from the booster charge.

If, by some remote chance, the cap and pellets should become prematurely detonated, the gas would immediately escape through a now uncovered port 68 in the housing 18 and expand in the case 14, and thus avoid exploding the booster charge 19. The arming plunger 53 thus serves the other one of its secondary functions. At this point it may be added that in practice the firing pin 67 (the pointed part of it) and the cap 20 will be duplicated, side by side, to obtain greater assurance of firing. Having provided this extra assurance, it is doubly important to hold the cap and pellets out of range when the exploder is unarmed, thus to guard against the contingency of accidental detonation.

The primary purpose of the plunger 53 is to arm the torpedo. This is done by rotation of the impeller 33, as has been brought out, and the consequent driving of the gear train 32, 31, 30, 26, 27 and the screw 37. The arming plunger is thus moved from the "in" position in Fig. 1 to the "out" position in Fig. 2. In arriving at that position the ring 58 no longer shields the pendulum 59 so that the latter becomes free to swing in any radial direction, and the cap 20 assumes registration with the firing pin.

Also in arriving in that position, the key 56 bears down on a pin 69 and rocks the bell-cranks 70, from the long arms of which it projects to bridge the distance between them (Fig. 6). The bell-cranks are fulcrumed at 72 to the relatively fixed housing 18, and as the rocking occurs links 73 pull on the pin 74 of a crosshead 75 to cause compression (Fig. 2) of the firing spring 76. For this purpose the ends of the links 73 are connected to the short arms of the bell-cranks 70 and to the ends of the crosshead pin 74. The latter rides in slots 78 in the sides of the firing pin barrel 79. The slots fix the limits of movement of the crosshead 75 in the bore 80 of the barrel.

When the spring 76 is compressed, the pin 67 is ready to fire the cap 20 and would do so were it not that the sear 81 which constitutes detent means holds the bolt 82 of the firing pin cocked. For that purpose one side of the bolt has a notch 83 occupied by a lug 84 protruding from the adjacent side of the sear. The other other side of the bolt has a slot 85 which contains the end of a headed stud or screw 86 driven through the barrel 79 into the bore 80. The stud prevents turning of the bolt but does not interfere with its rectilinear movement. The firing pin (or pins) 67 is secured into that end of the bolt nearest the plunger 53.

The opposite end of the bolt is cupped at 87 to contain most of the spring 76, especially in the cocked and armed position. The spring exerts

pressure against the crosshead 75 even when partly expanded as in Fig. 1 and thereby holds the bell-crank pin 69 firmly against the key 56 so that there never is any lost motion between the two. The free ends of the links 73 have key-hole slots 88 (Figs. 1 and 2) while the ends of the cross head pin 74 have annularly machined grooves (Fig. 6) to fit in them. The connection is made by simply inserting the heads of the pin 74 in the large parts of the keyholes, then sliding the necks as far back as they will go in the slots. This is a convenience in manufacture and assembly.

Going back to the cocked position of the firing pin bolt 82, it is observed in Figs. 1 and 2 that its holding sear 81 is under the permanent and inescapable control of the pendulum 59. This is accomplished by a rod 90, the ball ends of which are socketed in the sear and in the pendulum.

The stem 60 and rod 90 stay in the straight line shown as long as the torpedo remains unarmed and during its armed run, but in the last instance, when the pendulum lacks the restraint of the shielding ring 58, the impact of the torpedo with the target and its consequent jarring will deflect the pendulum. Since the swinging is on the arc of a circle, it follows that the rod 90 will be pulled upon and the sear will go with it. The consequent release of the bolt 82 from the lug 84 will enable the firing spring 76 to act.

The sear 81 is pivoted at 91 to and between ribs 92 (Fig. 4) that stand up from the barrel 79. These ribs also guide the sear in its rather small arc of movement, making sure that full advantage is derived from the canting of the rod 90. The free end of the sear has a contactable portion 93 which may be engaged by the foot 94 of a latch 95 to immobilize the sear. This latch always stands clear of the sear 81 (Figs. 1 and 2) and never moves from that position unless the torpedo should miss its target and sink at the end of its run to a depth in the sea whereat the hydrostatic pressure displaces the plunger 96.

A spring 97 of considerable strength ordinarily keeps the hydrostatic plunger extended in its packed passageway in the housing head 62. The extension is limited by the engagement of a cotter pin 98 or its equivalent with an adjacent part of the housing 18. One end of the spring bears against that part. The other end bears against the inside of a thimble 99 which houses most of it. The thimble slides on the stem end 100 of the plunger which, in turn, is slidable in the housing part and which has the cotter pin thrust through it. The thimble bears against the shoulder between the two diameters of the hydrostatic plunger, and it has a grooved collar 101 in which confronting studs 102 ride. These studs project inwardly of a portion of the latch 95 by which they are carried.

The latch 95 is pivoted at 103, and when the hydrostatic pressure forces the plunger 96 inwardly the latch 95 is rocked on its pivot until the foot 94 assumes a position over the portion 93. Then the sear cannot be lifted high enough by a swinging of the pendulum to release the bolt 82, hence the firing pin 67 remains cocked for an indefinite time. The same spring pressure which keeps the plunger 96 at the limit of its extension also holds the latch 95 tightly against the adjacent part of the housing 18. The latch does not swing freely, therefore will never get into position to obstruct the sear 81 in the normal operation of the torpedo.

Account is taken herein of the remote possi-

bility of operating the arming train, namely the impeller 33, the gearing and the arming screw 37, prior to loading the torpedo into the tube and to an extent wherein the arming plunger could be driven dangerously near the armed position in Fig. 2. This position is not to be assumed until the torpedo is well on its target run, and should any degree of arming be achieved prematurely that condition would show at the indicator spindle 104 (Fig. 4). This is a long-headed screw, the flat sides of the head of which bear against the correspondingly shaped bore 105 to permit extension but prevent turning of the indicator spindle.

To provide for the extension a worm wheel 106 with a swivel mounting on part of the housing 12 is screwed onto the threaded part of the stem. This wheel is driven by the worm 107 (Fig. 3) which is part of the shaft 103 that carries the gear 30, hence is part of the arming gear train. Normally the exposed end of the indicator spindle is flush with outer surface of the warhead shell 10, or nearly so (Fig. 4). The longer the arming train is prematurely operated, the farther will the indicator spindle emerge from its recess. If the operation continues until a dangerous degree of arming is reached the indicator spindle will protrude so far as to prevent loading of the torpedo into the tube.

The operation of the exploder, briefly reviewed, is as follows. The safety block 40 having been removed while loading the torpedo into a torpedo tube, and the torpedo having been launched from the tube, forward motion of the torpedo through the water causes rotation of the arming impeller 33. The gear train driven by it and the arming screw 37 move the plunger 53 from its "safe" position (Fig. 1) to its "armed" position (Fig. 2), with the following effects:

The percussion cap 20 is registered with the firing pin 67 and the pellets 66 are brought close to the booster charge 19. The firing spring 76 is compressed. The restraint imposed upon swinging of the firing pendulum 59 by the shielding ring 58 is removed. Subsequently, should the torpedo strike any object with such violence that the inertia of the firing pendulum overcomes the resistance of the spring 65, the firing pin bolt 82 is released from the sear 81 so that the firing pin 67 fires the warhead.

Should the torpedo run down without so striking any object, it will, according to standard practice and rules of warfare, sink. Having sunk to a predetermined depth it will be rendered safe against being detonated by the exploder, through the action of the hydrostatic plunger 98 and latch 95 and the sear 81. The last provision is considered desirable from a military point of view, since sinking torpedoes have exploded either due to hitting bottom or by sudden shock due to collapse of certain portions under hydrostatic pressure, thus disclosing an attack to the enemy.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. In an underwater torpedo exploder, an ex-

ploder case located in the warhead of the torpedo and containing an assembly of mechanism for detonating the warhead during the run of the torpedo toward a target, said mechanism including an impeller revolvable by a water flow past it to activate the mechanism, and a shield hinged on the case near the impeller initially closing off access of water to prevent such flow to the impeller but being swingable on its hinge to a displaced position to deflect water from the torpedo slipstream and divert some of said flow onto the impeller.

2. In an exploder for an underwater torpedo loadable into a tube for launching, said exploder having a firing train for the warhead, an impeller for assisting in arming the firing train, a shield hinged to a part of the exploder near the impeller, being in an initially closed position to prevent a water flow past the impeller but swingable on its hinge to an open position to deflect water onto the impeller from the slipstream of the torpedo after launching, and a block temporarily affixed to a part of the exploder, initially overlapping the shield to prevent opening thereof prior to the torpedo tube loading.

3. In an exploder for an underwater torpedo loadable into a tube for launching, said exploder having a firing train for the warhead, an impeller for assisting in arming the firing train, a shield hinged to a part of the exploder near the impeller, being in an initially closed position to prevent a water flow past the impeller but swingable on its hinge to an open position to deflect water onto the impeller from the slipstream of the torpedo after launching, a block protruding beyond the largest diameter of the tube and overlapping the shield to prevent premature opening, and a screw securing the block to a part of the exploder, being removable to take off the block to enable loading the torpedo into the tube.

4. In an exploder for an underwater torpedo loadable into a tube for launching, said exploder having a firing train for the warhead, an impeller for assisting in arming the firing train, a shield hinged to a part of the exploder near the impeller, being in an initially closed position to prevent a water flow past the impeller but swingable on its hinge to an open position to deflect water onto the impeller from the slipstream of the torpedo after launching, holding means protruding beyond the largest diameter of the tube and overlapping the shield to prevent premature opening, and manually removable means securing the holding means to a part of the exploder, being shearable upon striking of the holding means against the tube when loading the torpedo into the tube in the event of omitting manual removal of the last means preliminarily to said loading.

5. In an exploder for an underwater torpedo loadable into a tube for launching, said exploder having a firing train for the warhead, an impeller for assisting in arming the firing train, and a spring-biased shield hinged to a part of the exploder near the impeller, being held by the tube in an initially closed position to prevent a water flow past the impeller but swingable on its hinge to an open position by the spring bias to deflect water onto the impeller from the slipstream of the torpedo after launching.

6. In an exploder for an underwater torpedo loadable into a tube for launching, said exploder having a firing train for the warhead, an arming train for activating the firing train, including an impeller for operating the arming train, and an indicator spindle operatively coupled to the arm-

ing train, being initially retracted in the warhead shell but extensible by premature rotation of the impeller and consequent operation of the arming train, to indicate a dangerous degree of arming and preventing loading the torpedo into the tube.

7. In a torpedo exploder, said exploder having a firing train for the warhead of the torpedo, gearing including a driving impeller constituting an arming train for activating the firing train, and a spindle having an interthread connection with a part of the gearing, being initially retracted in the warhead shell but extensible therefrom as the gearing is worked by turning the impeller, which if done prior to loading the torpedo into the tube indicates a dangerous degree of arming and forms an obstruction to prevent said loading.

8. In a torpedo exploder adapted to be carried within a torpedo adjacent the warhead thereof, mechanism comprising: an arming member mounted for rectilinear movement within the exploder along a first axis, a firing pin mounted for rectilinear movement within the exploder along a second axis transverse to said first axis, a water actuated impeller carried by the exploder adapted to be rotated by the slipstream adjacent the torpedo, means operatively connecting the impeller and member for moving the latter along said first axis in response to rotation of the impeller, a firing train carried by the member having a terminal end at one side thereof disposed laterally of said second axis when the member is in unarmed position and adapted to be bodily moved with the member in a direction toward said second axis to armed position wherein it is disposed within the path of movement of the firing pin, and means operable independent of said mechanism for moving the firing pin into contact with said terminal end.

9. In a torpedo exploder, an initially unarmed arming plunger in the exploder containing a firing train for the warhead of the torpedo, a firing pin directed toward the path of movement of the plunger, a spring pressing the firing pin toward impact with the firing train, a sear retaining the firing pin, an impeller-operable arming train operatively coupled to the plunger to shift the plunger into arming position in respect to the firing pin, a key fixed on the arming plunger, and means operatively coupling the key and spring to build up spring pressure against the firing pin as the plunger approaches the armed position.

10. In a torpedo exploder, a plunger movable toward an armed position, said plunger containing a firing train exposed at least at one point, a firing pin initially non-registering with said exposed point, a spring tending to force the firing pin toward impact with the exposed point, a sear retaining the firing pin, a crosshead backing the spring, and a coupling between the plunger and crosshead, acting upon movement of the plunger to the armed position to compress the spring, storing energy which when released will cause the firing pin to impact the then registering exposed point.

11. In a torpedo exploder, an arming plunger movable toward an armed position and containing a firing train exposed at least at one point, a pivoted bell-crank having a pin loosely riding a part of the plunger, a crosshead having a link connection with the bell-crank, a firing pin, a spring between the crosshead and firing pin, acting through the link to keep the firing pin in contact with said plunger part and tending to force the firing pin to strike said exposed point when

the plunger arrives at its armed position, and a sear temporarily retaining the firing pin.

12. In a torpedo exploder, a spring-biased firing pin, detent means holding the firing pin in a cocked position, a pendulum coupled to the detent means and reacting to a jarring of the exploder to displace the detent means, an arming plunger containing a firing train exposed at least at one point to the firing pin when in an armed position but being movable to an unarmed position of non-registration of said point with the firing pin, and means carried by the plunger then embracing the pendulum to prevent its reaction to jarring.

15. 13. In a torpedo exploder, a spring-biased firing pin, detent means holding the firing pin in a cocked position, a pendulum coupled to the detent means and reacting to a jarring of the exploder to displace the detent means, an arming plunger containing a firing train exposed at least at one point, said plunger assuming an unarmed position whereat said point is out of registration with the firing pin, and a shielding ring carried by the plunger then embracing the pendulum to prevent its reaction to jarring.

20 14. In a torpedo exploder, a pendulum, an arming plunger assuming an unarmed position and containing a firing train exposed at least at one point, said plunger carrying a ring then embracing the pendulum to prevent its deflection, 30 detent means to which the pendulum is coupled for displacement, a firing pin held in a cocked position by the detent means, and an arming train coupled to the plunger, being operable to move the plunger to an armed position of registration of the exposed point with the firing pin and at the same time remove the ring from its embracement of the pendulum.

35 15. In an exploder for a submarine torpedo, a housing having a head exposed to the water, a firing pin guided in the housing, detent means to hold the firing pin in a cocked position, a latch pivoted near the detent means, a plunger coupled to the latch and extending through a packed bearing in the head for access to its end by the water, and a spring initially both keeping the plunger to the limit of its extension and swinging the latch on its pivot tightly against a part of the housing to stand clear of the detent means.

40 16. In an underwater torpedo exploder, an exploder case functionally integral with the warhead shell and having a stepped part, exploder and arming housings telescoped in each other then telescoped as a unit in the exploder case, 45 each of the housings containing respective exploder and arming mechanisms, a flange on the exploder housing on which the arming housing rests, said flange in turn being rested in the stepped part securing means by which the arming housing is secured to the exploder housing to compose a unitary structure of the two housings, and means securing the flange of the exploder housing to the stepped part of the exploder case independently of the arming housing, the removal of securing means of the arming housing enabling lifting out the arming housing without disturbing the mechanism in the exploder housing.

50 17. In a torpedo exploder, an exploder housing having a head, an arming plunger axially shiftably supported by said housing along a first axis and containing a firing train exposed at least at one point, a firing pin axially shiftably supported 55 by said housing along a second axis extending

transverse to said first axis with which said exposed point is registrable after being shifted along said first axis and toward said second axis, detent means carried by the housing and holding the firing pin in a cocked position prior to the arrival of said exposed point at the place of registration, a spring-biased pendulum under the head, and a stem and rod respectively swiveled to the head, pendulum and detent means, constituting a serial coupling which is operable to allow swinging of the pendulum in any radial direction and thereby produce a consonant dislodgement of the detent means, and means for continuously moving said plunger from its unarmed position to its armed position as the torpedo progresses through water.

18. In an exploder for a submarine torpedo, a firing pin, detent means holding the firing pin in cocked position, said detent means being pivoted at one end and having a contactable portion at the other end, a latch pivoted adjacently to the detent means, having a foot at one end, standing clear of but being in line with the contactable portion and having at its other end a portion with confronting studs, a spring-loaded thimble

riding the studs, and a plunger which is shouldered to bear on thimble, being hydrostatically operable to shift the thimble counter to its spring loading to swing the latch until its foot overlies the contactable portion thus to immobilize the detent means.

JOHN M. STOCKARD.
